UNITED STATES PATENT OFFICE.

JAMES E. WARLICK, OF LAGRANGE, GEORGIA.

BURGLAR-PROOF BLIND-LOCK.

No. 877,272.

Specification of Letters Patent.

Patented Jan. 21, 1908.

Application filed May 6, 1907. Serial No. 372,051.

To all whom it may concern:

Be it known that I, JAMES E. WARLICK, a citizen of the United States, residing at La-
5 grange, in the county of Troup and State of
Georgia, have invented certain new and use-
ful Improvements in Burglar-Proof Blind-
Locks, of which the following is a specifica-
tion.

My invention relates to improvements in
10 locks or fastenings especially for window
blinds or shutters.

Objects of the invention are to provide for
effectively fastening or securing the blinds
15 or shutters against being opened from the
outside, as with burglarious intent; and to
carry out that end with facility and sim-
plicity and inexpensively.

Said invention consists of certain struc-
20 tural features or instrumentalities substan-
tially as hereinafter fully disclosed and spe-
cifically pointed out by the claims.

In the accompanying drawing illustrating
the preferred embodiment of my invention—
25 Figure 1 is a front elevation thereof as in ac-
tual use. Fig. 2 is a transverse or horizontal
section produced through Fig. 1. Fig. 3 is
a detached perspective view of the stud-
equipped plate-member. Fig. 4 is a like
30 view of the latch-provided plate-member.

35 In the disclosure of my invention, I em-
ploy two plate-members 1 and 2 which are
adapted to be suitably applied or secured to
the meeting stiles of the blinds or shutters,
one upon the outside and the other upon the
40 inside thereof, respectively. The plate-
member 1, which is the outside one, has a
stud or pin 3 projecting from its inner sur-
face, near the forward edge, adapted for in-
spection through the window-stile and pas-
45 sage through an opening 4 in the plate-mem-
ber 2 lapping past the meeting edges of the
two stiles and accordingly upon the stile
through which passes said pin or stud, the
inner free end of the latter projecting beyond
50 the plate. Said stud or pin has a lateral slot
5 in its said projecting portion, and with said
slot is designed to engage a dog or latch 6
pivoted to the inside plate-member 2 as indi-

cated for effectively locking said stud in
place against being withdrawn or retracted 50
by the application of outside pressure or
force, thus rendering the fastening or lock
proof against any burglarious attempt to
open the shutters. Said latch has also a lat-
55 eral projection 7 for the ready application of
the finger or other means thereto from the
inside for conveniently disengaging said
latch from said stud or pin as in opening the
shutters or blinds in the usual way. It will
60 also be noted that the meeting edges of the
shutters, or their meeting stiles, are rabbeted
so that said edges may lap by each other and
thus guard against any attempted insertion
of a thin or bladed instrument between said
65 edges for engaging and withdrawing the
latch which might possibly otherwise be ef-
fected in that way.

The device is simple, relatively inexpen-
sive and effective for its intended purpose.

I claim—

70

1. As an article of manufacture, a shutter
fastener comprising a plate secured to the
shutter and having an integral stud, the side
of which stud is notched, and a catch pivoted
75 to swing in a plane parallel with said plate
and at right angles to the stud whereby to
enter the notch in the stud and lock the latter.

2. The combination with two shutters one
having a hole therethrough, of plates secured
thereto, one plate having an integral stud, a
side of which is notched, and the other having
an orifice adapted to be superposed over the
80 hole in the shutter, and a catch pivoted flat
to said latter plate and having an edge curved
approximately in the arc of a circle whose
center is the pivot whereby the curved edge
is adapted to take in the notch of the stud
85 when the shutters are closed and the notch
is in its path.

In testimony whereof I affix my signature, 90
in presence of two witnesses.

JAMES E. WARLICK.
